CLAIM

The ornamental design for a walkway paving stone, as shown and described.

DESCRIPTION

The present design relates to a decorative paving stone for use as the pavers for driveways, sidewalks, patios and the like.

FIG. 1 is a front elevation view of a walkway paving stone of the present invention;

FIG. 2 is a rear elevation view thereof;

FIG. 3 is a left side view thereof;

FIG. 4 is a bottom view thereof; and,

FIG. 5 is a perspective view thereof.
